UNITED STATES PATENT OFFICE

THOMAS CORNELIUS SHEEHAN, OF UPPER MONTCLAIR, NEW JERSEY, ASSIGNOR TO
WADE & BUTCHER CORPORATION, A CORPORATION OF NEW JERSEY

STROPPING MACHINE FOR RAZOR BLADES

Application filed July 26, 1928. Serial No. 295,596.

This invention relates to machines for stropping razor blades. The main object of the invention is to produce a simple and effective machine for automatically stropping 5 razor blades to a smoother cutting and more uniform edge than heretofore possible by machine stropping.

Hitherto, in machine stropping of razor blades, a great deal of trouble has been caused 10 by grit and foreign matter collecting on the blades and the strops, injuring both the delicate edge of the blade and the stropping surface. It has been found that by providing rotating cleaning wheels in contact with strop 15 surfaces and by providing cleaning means engaging the blade edges before stropping, the above difficulties can be avoided. It is, therefore, an object of the invention to produce a machine embodying these two improvements.

Also, in machine stropping of razor blades, long flexible strop belts have been found unsatisfactory in several respects. The belt joints must be quickly lifted before passing 20 the edge of the blade and then as quickly dropped on the edge after the joint has passed. This produces injurious vibration and is liable to injure the delicate edge unless elaborate precautions are taken to support the edge against the impact of the belt. Accordingly, it is an object of the invention to 25 provide a stropping element free from these disadvantages which, at the same time, retains the same stropping surface.

Still another object is to provide a machine 30 in which the portions of the delicate edge of the blades are kept in perfect alignment through passing over a considerable number of longitudinal aligned honing surfaces. Still another object is to provide effective 35 means to guide and steady the blades, particularly the new curved razor blades which are concave on one side and convex on the other, and to hold them in proper relation to the strop surfaces.

With these and other objects not specifically stated in view, the invention consists in certain constructions and combinations which will be hereinafter fully described and 40 then set forth in the appended claims.

In the accompanying drawings which form a part of this specification and in which like characters of reference indicate the same or like parts:

Figs. 1 and 2 are respectively left and right 45 hand halves of a complete plan view of a stropping machine in accordance with the invention;

Fig. 3 is an end view, partly broken away, of the machine shown in Figs. 1 and 2;

Fig. 4 is an enlarged detail view looking at the side of the spring fingers on the concave side of the blade;

Fig. 5 is a detail sectional view of the strop on the concave side of the blade showing its 55 relation to the blades and the cleaning wheels;

Fig. 6 is a similar view to that in Fig. 5, showing the strop on the convex side of the blade; and

Figs. 7 and 8 are side views showing the 60 concave and convex sides of the blade.

In carrying the invention into effect, there is provided means for forwarding razor blades with an edge exposed, a strop movable in the path of the edge for stropping the 65 same, and means for simultaneously driving the strop and cleaning grit or dirt from said strop. In the best constructions, the means for driving and cleaning the strop will include a power driven cleaning wheel in engagement with the strop. In the best constructions, there is provided means for forwarding razor blades in a right line with an edge exposed, a pair of rotatable shafts parallel and on either side of the path of the 70 blades, and a series of strops secured circumferentially about each of said shafts for rotation in the path of the exposed edge of the blades. In the best constructions, the strops on one shaft are staggered with respect to those on the other shaft and the strops on one shaft projecting into the spaces between the strops on the other shaft. In the preferred form, a series of rotating cleaning 75 wheels are in frictional engagement with each strop of the series. Preferably, the stropping element comprises a rotating member having a cylindrical surface concentric with its axis of rotation and a strop belt circumferentially wrapped about said cylindri- 80 85 90 95 100

cal surface, which is secured thereon with its ends within the cylindrical stropping surface formed by the belt. The means above referred to may be widely varied in construction within the scope of the claims, for the particular machine selected to illustrate the invention is but one of many possible embodiments of the same. The invention, therefore, is not to be restricted to the precise details of the structure shown and described.

Referring to Figs. 1 and 2 of the drawings, tables 10, 11 and 12 are connected by girders 13 and 14 supported by frames 15, the whole constituting the main frame of the machine.

15 Supported on the tables 10 and 11 is a narrow steel forwarding belt 16 provided with lugs 17 for engagement of the perforations in the slot of the blades 18 to support the same. This belt is carried by a pair of pulleys 20 and 22, the former of which is rotatably mounted on a stub shaft 21 supported in a slide on the table 11 for adjustment in a conventional manner to tension the belt. The pulley 22 is journaled on the table 10 and is 20 driven by a suitable drive means, not shown, supported under the table.

In order to hold the blades on the forwarding belt and to provide a smooth guide surface for the convex side of the blades, a stationary belt 25, having one run extending parallel with and in close proximity to the belt 16, is supported on pulleys 26 and 27 mounted respectively on a shaft 28, which is 30 adjustable to tension the belt, and a stationary shaft 29.

The blades are automatically fed from the stack 31 on arbors 32 against the forwarding belt, the blades being carried one by one between guides 33 and 34 into forwarding position between the stationary and forwarding belts, by which the blades are carried to the cleaning wheels 37 and 42. The particular construction of the automatic blade feed is not part of the present invention, reference being made to copending application filed July 26, 1928, S. N. 29,597, for a more detailed disclosure.

To remove burr and grit left on the blade edges in previous grinding or honing operations, two series of cleaning wheels 37 and 42 arranged, respectively, on the concave and convex sides of the blades are provided. The wheels 37 are mounted in spaced relation on a shaft 38 journaled in bearings 39. The cleaning wheels 42 on the convex side of the blade are supported in spaced relation upon a shaft 43 journaled in bearings 44 which support the wheels 42 somewhat above the wheels 37, in order that these wheels may engage the concave and convex sides of the edge at approximately the angle of the honed surfaces of the blade. The bearings 39 and 44 are bracketed to platforms 45 which are slidable on cross rods 46 secured to the girders 13 and 14, and these platforms are ad-

justable on the cross rods towards and away from the path of the blades by conventional handscrews (Fig. 1). The shafts 38 and 43 are driven by conventional pulleys 47 and 48. It is noted that the wheels 37 are staggered with respect to the wheels 42 and each set of wheels projects into the space between the other set, in order that they may rub on the edge of the blades along surfaces intersecting said edge. Another advantage of this arrangement is that the wheels occupy less space along the forwarding means and the wheel on one side tends to support the blades against the wheels on the other side of the blade.

To support and guide the blades on the forwarding means as they pass the cleaning wheels and the strops, to be presently described, there is provided a pair of elongated guide plates 51 and 52 bracketed to the tables 10, 11 and 12, on each side of and close to the path of the blades. Each of these guide plates has flat vertical surfaces 53 and 54, the former bearing against the forwarding belt and the latter bearing against the stationary belt to hold said belts together, with the blade held firmly between them. These plates are tapered to a narrow upper edge in order to fit between the blades and the wheels, or strops. The upper horizontal edge of the stationary belt 25 provides a surface on which the lugs of the belt 15 ride and thus prevents vertical whipping of the same. The groove, or recess 55 of the guide plate 51 provides clearance for the lateral curvature of the blade (Figs. 5 and 6).

It is noted that the belts 16 and 25 have considerable depth, being much wider than the width of the blades, and that the belt 16 is slotted near its upper edge to receive the lower edge of the blade, thus leaving a narrow belt portion at the upper edge of the belt which fits snugly in the concavity of the blade. The lower portion of the belt 16, which extends beyond and below the lower edge of the blades, thus provides a broad surface to guide on the plate 51.

Further forwarding of the blades, after passing the cleaning wheels, brings the blades to a series of strops 60 and 61 on each side of the path of the blades. The strops 60 on the concave side of the blades are axially aligned on a series of cylindrical enlargements 64 on a shaft 62. These strops consist of a short length of strop belting circumferentially wrapped about the enlargements 64 on the shafts with the ends of the belt in a V groove 65 in which is fastened a block 66, also V shaped, by the screw 67 which draws the ends of the belt together and clamps them in the groove with the ends well below the cylindrical stropping surface formed by the belts. The shaft 62 is journaled in bearing blocks 68 having shanks

69 secured for vertical movement in slide-ways on brackets 70 secured to the tables 10 and 11. The shaft 63 carrying strops on the convex side of the blade is identical in construction with that on the concave side already described and is supported in the same way, except that the bearing blocks 68 are higher in position in order that the strops may engage the blade edge at the proper angle. Accordingly, further description of this series of strops and its bearings is omitted for the sake of brevity.

As with the cleaning wheels, the strops on one shaft are staggered with relation to those on the other stropping surface on one side of the path of the blades, entering a little into the space between the strops on the other side of the blade so that the strops may engage the blades along the surfaces intersecting at the edge, as shown in Figs. 5 and 6.

To hold the edge of the blades against the strop, there is provided a series of fingers 71 holding the blade edges against the strop on the concave side of the blade and a series of fingers 72 holding the blade edges against the strop on the convex side of the blade. These fingers are of substantially the same width as the width of each strop, and thus they act to hold the blade in alignment for its entire passage across the face of the strop. Since a large number of strops is used and the strops travel relatively fast, only a light pressure is needed by each finger on the blades, the fingers being secured for this purpose to the plates 51 and 52 by means of screws 73 and slots 74 which, as shown in Fig. 4, permit slight vertical adjustment.

To clean grit and other foreign matter off the stropping surfaces simultaneously with the driving of the strops, a series of felt wheels 75 are mounted in frictional engagement with the strops on a pair of shafts 76 and 77 extending parallel to the shafts 62 and 63 and supported from the girders 13 and 14 by brackets 79 carrying bearing blocks 78. The screw and slot connection between the brackets 79 and the girders permits adjustment of the frictional engagement of the wheels with the strops. The shafts 76 and 77 are driven by pulleys 81 and 82 belted to a motor 83 mounted on the frames 15. The strop carrying shafts are independently driven by motors 84 and 85 having belts 86 and 87 running over pulleys 88 and 89 on shafts 62 and 63. Since the cleaning wheels and the strops are independently driven, they will be driven ordinarily at a slightly different peripheral speed, though in the same direction, in order to cause a brushing action due to the difference in their speeds. At the same time, the power driven cleaning wheels will supplement the driving of the strops by the motors 84 and 85.

After passing the strops, the blades pass between the takeoff guides 90 and 91, after which the spring ejector 92 forces the blades on to arbors 93 where the blades form a stack 94. The particular construction of the blade ejecting and stacking device is not a part of the present invention, reference being made to a copending application S. N. 295,597, filed July 26, 1928, for a more detailed disclosure of the same.

It will be noted that since the blades contact a large number of longitudinally aligned strops, the wear on any one strop will be relatively slight. Moreover, the resulting large longitudinal stropping action has the effect of aligning the portions of the delicate edge to provide a smoother cutting edge. As will be seen from Figs. 7 and 8, the small diameter of the strop surfaces and their arrangement so that they strop surfaces intersecting at the edge of the blade, provides a hollow honed edge of the desired thinness, backed by a closely adjacent thicker portion which enables the blade to hold its edge. It should also be observed that the arrangement of the strops on one side of the blades close to and projecting between the adjacent strops on the other side of the blades (Figs. 1 and 2) is such that the former assist in guiding and holding the blades against the latter.

The lugs 17 on the travelling blade forwarding belt 16 engage in slots of the curved blades in the stack 31 and carry the blades past the cleaning wheels 37 and 42, and the strops 60 and 61. The blades are held on the forwarding belt by a stationary belt 25 engaging the convex side of the blades and supporting the lugs on its upper edge. To further support and guide the blades on the forwarding belt, flat vertical guide surfaces 53 and 54 on a pair of elongated guide plates 51 and 52 bear against the forwarding and stationary belts respectively. After passing the cleaning wheels, the blades are pressed against the strops by fingers 71 which act to hold the blades in alignment for their entire passage across the faces of the strops. Upon leaving the strops the blades pass between takeoff guides 90 and 91, after which the spring ejector 92 forces the blades on the arbors 93 where they form a stack 94.

What is claimed is:

1. In a stropping machine for curved razor blades, the combination with means for forwarding curved razor blades in a straight line path with an edge exposed, of a rotatable shaft parallel to the path of said blades, a series of strops on said shaft in the path of the exposed edge of the blade, and a series of rotating cleaning wheels in frictional engagement with said strops to clean them, said means including a blade forwarding belt provided with a series of slots to receive the other edge of the blades.

2. In a stropping machine for curved razor blades, the combination with means for forwarding razor blades in a straight line path with an edge exposed, of a pair of rotatable shafts parallel to and on either side of the path of the blades, a series of strops on said shafts in the path of the exposed edge of the blades, a spring finger cooperating with each strop to hold the blades against said strop, 10 said spring finger having a blade engaging portion extending along the edge of the blade for substantially the width of the blade, and said means including a blade forwarding belt provided with a series of slots adapted to receive the other edge of the blades. 15
3. In a stropping machine for curved razor blades, the combination with means for forwarding curved razor blades with an edge exposed, of a strop rotating in the path of the 20 exposed edge of the blades, and a device for cleaning the strop, said means including a blade forwarding belt provided with a series of slots adapted to receive the other edge of the blades. 25
4. In a stropping machine for curved razor blades, the combination with means for forwarding curved razor blades with an edge exposed, of a strop rotating in the path of the exposed edge of the blades, and a device 30 for cleaning said strop, said means including a blade forwarding belt provided with a series of slots adapted to receive the other edge of the blades, and said device including a power driven felt wheel in engagement with the strop. 35
5. In a stropping machine for curved razor blades, the combination with means for forwarding curved razor blades in a straight line path with an edge exposed, of a strop movable in the path of the exposed edge of the 40 blades, a device for cleaning the strop, and mechanism cooperating with the forwarding means to remove burr and grit from the exposed edge of the blades prior to stropping, 45 said means including a blade forwarding belt provided with a series of slots adapted to receive the other edge of the blades. 50
6. In a device for stropping curved razor blades, the combination with means for forwarding curved razor blades with an edge exposed, of a rotating member having a grooved cylindrical surface concentric with its axis of rotation and a strop belt adapted to engage the exposed edge of the blades and 55 circumferentially wrapped about said surface with its ends within said groove, said means including a blade forwarding belt provided with a series of slots adapted to receive the other edge of the blades. 60
7. In a device for stropping curved razor blades, the combination with means for forwarding curved razor blades with an edge exposed, of a rotating member having a grooved cylindrical surface concentric with its axis of rotation, a strop belt circumferen- 65

tially wrapped about said surface and secured thereon with its ends within said groove, and a block fastened in said groove to clamp the ends of the strop belt in said groove, said means including a blade forwarding belt provided with a series of slots adapted to receive the other edge of the blades. 70

In testimony whereof, I have signed my name to this specification. 75
